UNITED STATES PATENT OFFICE.

ARNOLD J. WEST, OF ABERDEEN, WASHINGTON.

OFFSET MECHANISM FOR SAWMILL-CARRIAGES.

SPECIFICATION forming part of Letters Patent No. 732,148, dated June 30, 1903.

Application filed February 11, 1903. Serial No. 142,890. (No model.)

To all whom it may concern:

Be it known that I, ARNOLD J. WEST, a citizen of the United States, residing at Aberdeen, in the county of Chehalis and State of Washington, have invented a new and useful Offset Mechanism for Sawmill-Carriages, of which the following is a specification.

My invention relates to offset mechanism for sawmill-carriages. Its object is to provide an offset mechanism of exceedingly simple construction which is adapted to be applied to sawmill-carriages of ordinary form with but little modification of the carriage and but small cost. This object is attained in the construction and combination of parts hereinafter fully described and claimed, and shown in the accompanying drawings.

Referring to the drawings, Figure 1 is a plan view of a sawmill-carriage provided with my improved offset mechanism. Fig. 2 is a longitudinal section showing in solid lines the position of the parts when the carriage is moving forward to feed a log to the saw and showing in dotted lines the position of the parts of the offset mechanism after the carriage has been gigged. Fig. 3 is a transverse section across the carriage along the line 3 3 of Fig. 1. Fig. 4 is a detail view showing in side elevation the shrouded disk 16 and the split collar mounted thereon. Fig. 5 is a vertical section through Fig. 4. Fig. 6 is a detail showing the threaded block 13 in section and the screw-shaft 11 in engagement therewith. Fig. 7 is a view in longitudinal section of a modified form of the invention, showing the offset bar supported below the axles on the sawmill-carriage and the connecting-rod 22 passing through a suitably-placed opening in the cross-bar 3 of the carriage-frame. Fig. 8 is a transverse section of the modified form of my invention shown in Fig. 7 looking toward the right.

The sawmill-carriage, as shown in the drawings, consists of side members 1 1, end members 2 2, and a central cross-beam 3. This frame is supported on wheels 4 4 4, rigidly secured to axles 5 5, and is susceptible of lateral movement upon said axles between stop-collars 6 6, carried by each axle and limiting the movement of the journals 7 7 upon each axle.

8 is a bar, which will be hereinafter re-

ferred to as the "offset" bar, extending longitudinally of the carriage and being supported upon the axles, for which journals 9 9 are provided near its ends. At a slightly-greater distance from each end of the bar 8 are provided journals 10 10 for shafts 11 11, each shaft having at one end an enlarged portion 12, which is provided with screw-threads to engage with the correspondingly screw-threaded block 13, secured to one of the side members 1 of the frame of the carriage.

In order to prevent any movement of the axles 4 or the shafts 11 in their bearings in the offset bar 8, collars 14 14 14 14 are rigidly secured to the axles in the manner shown, and similar collars 15 15 15 15 are rigidly secured to the shafts 11.

Rigidly secured to each axle is a shrouded disk 16, and surrounding the periphery of each of said shrouded disks is a split collar 17, having adjusting-screws 18 18 to compensate for wear, and friction-surfaces of suitable material provided on the inner surface 75 of the split collars to engage with the periphery of the disks 16 16. Projecting from the lower member of the split collar 17 are radial arms 19 19. Rigidly secured to the screw-shafts 11 and arranged parallel to the radial arms 19 19 are other radial arms 20 20, and securing said arms 19 19 and 20 20 in parallel position are connecting-rods 21 21. In order to insure perfect synchronism in action between the two screw-shafts 11 11, a connecting-rod 22 connects the radial arms 20 20, and adjustably mounted on said connecting-rod 22 are two stop members 23 23, adapted to engage with the central transverse beam 3 of the carriage-frame. Rigidly secured to one 90 of the screw-shafts 11 is a lever 24, whose function will be hereinafter explained.

It will be seen from the accompanying drawings that when motion is imparted to the carriage in order to feed a log to the saw the axles 5 5 will be rotated in the direction shown by the arrow in Fig. 2. This rotation of the axles is imparted to the split rings 17 17 and from them through the radial arms 19 19, connecting-rods 21 21, and radial arms 20 20 to the screw-shafts 11 11. This movement causes the connecting-rod 22 to be carried rearwardly until the forward stop 23 rests against the forward surface of the cross-beam 3, which pre-

vents any further movement, and therefore the split rings 17 17 slip upon the disks 16 16 during the continuance of the feeding movement of the carriage. When the motion of 5 the carriage is reversed, the axles 5 5 will be caused to rotate in a direction opposite to that just described, and a corresponding movement will be imparted to the split rings 17 17 and the radial arms 19 19 extending 10 therefrom. This rotation will be imparted to the screw-shafts, causing them to move inward along the screw-threaded portions of the blocks 13, causing a corresponding movement of said blocks 13 13 upon the enlarged 15 portions 12 12 of the screw-shafts. Now owing to the presence of the collars 15 15 15 15, which prevent any longitudinal movement of the screw-shafts 11 in their journals in the offset bar 8, and the collars 14 14 14 14 on the 20 axles 5 5 to prevent any lateral movement of the offset bar on the axles the screwing of the shafts 11 into the blocks 13 causes the frame of the sawmill-carriage, to which the blocks 13 13 are firmly secured, to be shifted 25 laterally upon the axles 5 5.

The extent of the lateral movement of the carriage is determined, as will be readily seen, by the amount of rotation of the screw-shafts 11 in the blocks 13 and the pitch of the 30 screw-threads. The pitch of the screw-threads employed may be of any convenient degree, and the amount of rotation may be determined at will by shifting the stops 23 23 upon the connecting-rod 22 22.

35 It is sometimes desirable to reverse the motion of the sawmill-carriage before the cut is applied, and when this is done any lateral shifting of the carriage must be prevented. In order to provide for such reverse movements of the carriage without offsetting, the 40 lever 24 is provided. As the carriage moves forward this lever is inclined forwardly, as shown in full lines in Fig. 2, and when the carriage has been offset by the automatic 45 mechanism already described it occupies the rearwardly-inclined position shown in dotted lines in the same figure. It will be seen that if it is desired to reverse the movement of the carriage without offsetting all that is necessary 50 is to hold the lever 24 in the forwardly-inclined position, for when this is done the split rings 17 17 slip upon the disks 16 and no rotation is imparted to the screw-shafts 11 11.

In the modified form of the invention shown 55 in Figs. 7 and 8 the offset bar is supported below the axles and journals for the axles, and screw-shafts are provided in blocks screwed to the bar 8 instead of in the bar itself. The radial arms 19 and 20 are attached to the upper parts of the split collars,

and connecting-rod 22 lies in a plane above that of the axles and screw-shafts and passes through a suitable opening in the cross-bar 3, which permits the required amount of vertical movement of the connecting-rod. The 65 operation of this form of my invention is so nearly like that of the form already described in the preceding pages that no detailed account of the operation of the modified form is regarded as necessary. 70

In the foregoing description and in the accompanying drawings I have disclosed a preferred form of my improved offset mechanism for sawmill-carriages; but it is to be understood that various modifications and 75 changes might be made therein without departing from the spirit of my invention, and I do not wish to be limited to the exact form and proportions shown and described.

What I claim as new, and desire to secure 80 by Letters Patent, is—

1. In a mechanism of the character described, a sawmill-carriage frame shiftable laterally on its axles and provided with a transverse beam, a bar extending longitudinally of said frame journaled on said axles and secured against lateral movement on said axles, screw-shafts journaled in said bar, threaded blocks secured to said frame and in engagement with said screw-shafts, friction 85 devices carried by the axles, connections between said friction devices and said screw-shafts, radial arms on said screw-shafts, a connecting-rod between said radial arms, and stop members carried by said connecting-rod, 90 substantially as described. 95

2. In a mechanism of the character described, a sawmill-carriage shiftable laterally on its axles and provided with a transverse beam, a bar extending longitudinally of said frame journaled on said axles and secured against lateral movement thereon, screw-shafts journaled in said bar, threaded blocks secured to said carriage-frame and in engagement with said screw-shafts, friction devices 100 carried by the axles, connections between the friction devices and said screw-shafts, radial arms on said screw-shafts, a connecting-rod between said radial arms, and adjustable stop members carried by said connecting-rod and adapted to contact with said transverse beam, substantially as described. 105 110

In testimony that I claim the foregoing as my own I have hereto affixed my signature in the presence of two witnesses.

ARNOLD J. WEST.
